HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

EQUALIZER FOR ROCK DRILLS.

Application filed September 11, 1925. Serial No. 55,677.

This invention relates to rock drills, but more particularly to an air cushioned equalizer for supporting the drill steel of fluid actuated rock drills of the hammer type.

5 In drilling long holes for analytical, or other purposes, it is at times desirable to penetrate the rock to a depth greatly in excess to that for ordinary mining operations. Owing to the impracticability of using a 10 single steel of the desired length, the steel is usually made in sections to be connected in any convenient manner as for instance screw threads. In this way, as the steel penetrates the rock, sections may be added 15 until the desired depth has been drilled. Such additions, however, add greatly to the weight of the steel, which weight, during up-hole drilling is usually supported by the chuck parts of the drill and cause considerable wear on these parts.

It is accordingly an object of the invention to protect the chuck and associated parts against wear by preventing endthrust of the steel against the chuck.

25 Other objects will be in part obvious and in part pointed out hereinafter.

The invention consists of the combinations of elements, features of construction, and arrangement of parts having the general mode of operation substantially as hereinafter described and more particularly pointed out in the appended claims and illustrated in the accompanying drawings, in which

35 Figure 1 is an outline view of a rock drill mounted on a column and illustrating the manner in which the equalizer supports a heavy drill steel during inclined long hole drilling, and

40 Figure 2 is a longitudinal view, partly in section, of the front end of a rock drill equipped with an equalizer constructed in accordance with the practice of the invention.

45 Referring to the drawings, and more particularly to Figure 1, a drill A is shown supported by a shell B having a feed screw C which cooperates with the drill A and whereby the drill may be advanced towards the 50 work as the drill steel D penetrates the rock or other material to be drilled. In this instance, the shell B is secured to a suitable clamp E which holds the drill against rota-

tive movement. The clamp E is mounted on a column F extending from the floor of a drift G to its roof and has a pair of screw jacks H whereby the said column may be held firmly in position.

Ordinarily in rock drills of the hammer type, the drill steel D is supported within a front head J but in this instance, said steel is supported by an air cushioned equalizer K abutting the front head J. The equalizer K has a cylinder L to receive a piston O. The piston O in this instance has a bore P to receive slidably a shank Q of the drill steel D. The shank Q has a reduced portion R which extends beyond the equalizer and into the front head J.

In order to impart rotary movement to 70 the shank Q and consequently to the drill steel D, the reduced portion R of said shank carries wings S which interlock slidably with flats or keys T formed in a chuck jaw U. The chuck jaw U is rotatable within the 75 front head J and has opposed grooves V to permit entrance of the wings S into the said chuck. The median line of the grooves V preferably intersects the median line of the keys T at right angles so that during the 80

normal operation of the drill the wings S are out of line with the grooves V. In this way the shank Q is held against accidental removal from the chuck jaw U. The inner face of the chuck jaw U may be castellated 85 as at W to engage similarly formed castellations on a chuck X for the purpose of preventing relative movement between said chuck jaw U and the chuck X. The chuck X in this instance extends into a cylinder 90 Y and has inwardly extending ribs Z which cooperate with similar ribs 5 formed on a reciprocating hammer piston c, only a portion of which is shown, and which is adapted to deliver blows of impact against the end 95 of the shank Q. Any suitable and well known rotation mechanism may be employed for imparting rotative movement to the chuck parts and the drill steel. A chuck bushing d inserted in the front end of the 100 chuck X serves both as a guide for the reduced portion R of the shank Q and also to limit longitudinal movement of said shank in one direction.

In order to advance the piston O in the 105 cylinder L, a connection e, preferably in the

form of a flexible hose, is secured to the equalizer K and communicates with the rearward end of the cylinder L through a passage f for supplying pressure fluid to said cylinder. The connection e may communicate either directly with a supply of pressure fluid or may be connected with a hose g which supplies pressure fluid to the drill for operating the hammer piston c. A valve h is attached to the connection e for controlling the admission of pressure fluid and the exhaust of pressure fluid from the cylinder L. The valve h may be of any suitable type, but is preferably of the two-way type so that the exhaust of the pressure fluid from the cylinder L may be effected through the valve to the atmosphere.

To the end that the piston O may be at all times retained within the cylinder L, a groove j is formed in the front end of the cylinder L to receive a split expansible spring ring k. The ring k is so located with respect to the piston that during the normal operation of the drill the piston O will not strike said ring and is employed chiefly for preventing removal of the piston when the equalizer K is detached from the drill. A shoulder o is in this instance formed on the shank Q to cooperate with the piston O for limiting longitudinal movement of the piston O on the shank Q in one direction. The shank Q is preferably screw threaded as at p to receive a correspondingly screw threaded end of the drill steel D.

In the operation of the device, let it be assumed that the drill A is positioned for up-hole drilling as indicated in Figure 1. In this position of the drill, the drill steel D tends to slide rearwardly so that the wings S of the shank Q bear directly against the chuck nut d and due to the weight of the steel force the chuck X rearwardly against the cylinder Y, thus causing considerable wear on the contacting faces of these parts and also adding greatly to the resistance to rotation. To relieve the chuck X of the weight of the drill steel D, the valve H may be turned to a position to admit pressure fluid into the bore L rearwardly of the piston O. Pressure fluid thus admitted into the bore L will move the piston O forwardly against the shoulder o of the shank Q and move the wings S out of contact with the chuck busing d. In this way the pressure fluid in the rearward end of the bore L will serve as a cushion against which the thrust of the drill steel may act, and since the equalizer K abuts the front end of the front head J, the weight of the drill steel D is transferred to the front end of the front head J.

The above described equalizer may be readily attached to or detached from a rock drill and, if desired, may become a permanent part of the rock drill since the reduced

portion R of the shank Q is identical in every respect with the ordinary drill steels of this type, so that only the shank Q may be removed and ordinary drill steels may be inserted into the chuck. 70

Although the equalizer is described as being secured to the front head, it is to be understood that said equalizer may be abutted loosely against the front head in which case it will be supported entirely by the shank Q. In either case the shank Q serves to directly centralize the equalizer with respect to the front head.

I claim:

1. In a fluid actuated rock drill, the combination with a front head, a chuck in the front head, and a drill steel extending into the chuck, of a cylinder abutting the front end of the front head and centralized therewith directly by the drill steel, and a fluid actuated piston in the cylinder to support the weight of the drill steel. 80

2. In a fluid actuated rock drill, the combination with a front head, a chuck in the front head, and a drill steel slidable in the chuck, of a cylinder abutting the front end of the front head and centralized with respect thereto directly by the drill steel, and a fluid actuated piston in the cylinder to slidably support the drill steel for relieving the chuck of the weight of the drill steel. 90

3. In a fluid actuated rock drill, the combination with a front head, a chuck rotatable in the front head, a drill steel slidable in the chuck and rotated thereby, and a collar 100 on said drill steel, of a cylinder abutting the front end of the front head and held coaxial therewith directly by the drill steel and a fluid actuated piston in the cylinder to slidably receive the drill steel and abut the collar to protect the chuck against the thrust of the drill steel. 105

4. In a fluid actuated rock drill, the combination with a front head, a chuck rotatable in the front head, a drill steel extending into the chuck and rotated thereby, and a collar on said drill steel, of a cylinder secured to the front end of the front head, a fluid actuated piston in the cylinder to slidably receive the drill steel for protecting 110 the chuck against the weight of the drill steel and an expansible ring in the cylinder for retaining the piston within the cylinder. 115

5. In a fluid actuated rock drill, the combination with a front head, a chuck rotatable in the front head, a drill steel extending into the chuck and rotated thereby, and a collar on said drill steel, of a cylinder secured to the front end of the front head, a fluid actuated piston in the cylinder to receive slidably the drill steel for protecting the chuck against the weight of the drill steel, an expansible ring in the cylinder for retaining the piston within the cylinder, and means for admitting pressure fluid to the 125

rear end of the cylinder for actuating the piston forwardly and for exhausting pressure fluid from the cylinder.

6. In a fluid actuated rock drill, the combination with a front head, a chuck rotatable in the front head, a drill steel extending into the chuck and rotated thereby, and a collar on said drill steel, of a cylinder secured to the front end of the front head, a fluid actuated piston in the cylinder to receive slidably the drill steel for protecting

the chuck against the weight of the drill steel, an expansible ring in the cylinder for retaining the piston within the cylinder and manually controlled means for admitting 15 pressure fluid to the rearward end of the cylinder for actuating the piston forwardly and for exhausting pressure fluid from the cylinder.

In testimony whereof I have signed this 20 specification.

CHARLES C. HANSEN.
